WINDOW FRAME

Philip R. Oftedal, Donald G. Kingsley, and
Willard Congreve, Chicago, Ill.

Application June 12, 1935, Serial No. 26,176

2 Claims. (Cl. 189—65)

Our invention relates to window construction and more particularly it relates to improvements in hollow window frames and sashes cooperating therewith.

- 5 The invention is especially adapted for hollow window frames for double hung windows, the frame providing vertical slots extending substantially its full length and the sashes having laterally projecting side members extending 10 through the slots and into the chambers provided by the vertical portions of the frame. The slots are adapted as guides for the sashes in raising and lowering the same and also are adapted to prevent side movement of the sashes. 15 When the sashes are in closed position, the lower portions of the slots for the top sash and the top portions of the slots for the lower sash form substantial openings respectively connecting the frame chambers with the outside atmosphere and with the interior of the room. 20 It is found in practice that frame chambers having the described slotted openings function as conduits for the entrance of air into the room from the outside in an amount largely nullifying the effect of weather stripping with which the 25 sashes and frames are ordinarily equipped. The chambers in the window frames collect dust and other floating particles which enter through the uncovered portions of the slots and settle to the bottom of the chambers where they collect in quantities which sooner or later requires dismantling of the frames to permit its removal. Not only is the dismantling of the frames for this purpose a time consuming and expensive operation, the 30 necessity for which it is one of the objects of the invention to prevent, but the slots also permit the entrance into the relatively large frame chambers of vapor, rain and snow which causes the chambers to remain damp for long periods of time 35 with the result that the frames prematurely disintegrate by rusting on the inside.

40 The invention consists in the provision of closure members connected with the frames at the marginal edges of the slots and projecting into the chamber to form runways in which the laterally projecting sash members fit snugly and cooperate therewith to prevent side movement of the sashes and, by reason of their uniform but slightly yielding contact with the sash members, 45 enable the sashes to be easily raised and lowered. The closure members prevent the entrance of moisture and floating particles into the chambers and also prevent the chambers from acting as conduits through which air enters the room 50 from the outside and vice versa.

Still another object of the invention is the provision of improvements for hollow or chambered window frames of the kind described which are adapted to be manufactured cheaply, are simple, durable, easily installed and removed and 5 satisfactory for their intended purpose.

Many other objects and advantages of the construction herein shown and described will be obvious to those skilled in the art from the disclosure herein given.

10 To this end, our invention consists in the novel construction, arrangement, and combination of parts herein shown and described, and more particularly pointed out in the claims.

15 In the drawing, wherein like reference characters indicate like or corresponding parts:

Fig. 1 is a vertical section through a window equipped with devices embodying the principles of the invention;

Fig. 2 is a section along the line 2—2 of Fig. 1 20 showing the devices embodying the principles of the invention and also showing fragmentary portions of double hung sashes cooperating therewith; and

Fig. 3 is a perspective view of a closure member 25 positioned within and detachably connected with the hollow frame as shown in elevation in Fig. 1 and in section in Fig. 2.

Referring now more particularly to the drawing, the numeral 10 designates a hollow window 30 frame generally illustrative of any one of a plurality of shapes in general use and all of which provide a relatively large chamber 11 extending from top to bottom of the window on each side. The side walls of the frame adjacent the sashes 35 provide slots 12 and 13 respectively in alignment with the adjacent edges of upper and lower sashes 14 and 15. The sashes 14 and 15 have side extension members 16 which respectively project through the slots 12 and 13 into the frame 10. 40 The slots 12 and 13 extend substantially the full height of the window and the cooperating frames and sash members are usually equipped with weather stripping to prevent entrance of air past the edges of the sashes and into the chambers 11. 45 It is obvious that when the sashes are closed the lower portions of the slots 12 are uncovered and connect the chambers 11 with the outside atmosphere and that the upper portions of the slots 13 are similarly uncovered and connect the 50 chambers with the interior of the room.

The chambers 11, opening as described both into the outside atmosphere and the interior of the room, act as conduits through which outside dust laden or cold air, or both, enters the room 55

in substantial volume notwithstanding the provision of weather strips. The heavier particles carried by the air collect in the bottom of the chambers 11 as previously described and the 5 lighter particles enter the room and settle upon the furniture, floor and walls. Experiments have shown that the chambers 11 act as siphons through which the outside air enters the room when the sashes are closed, the experiment consisting in placing a supply of dry white powder 10 in the bottom of the chamber 11 when the outside temperature is below that of the room. The powder enters the room through the uncovered portion of the slots 13 in streams which are visible to the eye and small deposits of such powder 15 in the chamber are soon exhausted. The cold air entering the room in this manner is of a volume sufficient to perceptibly lower the temperature of the room, resulting in the waste of heat by the 20 intermittent, if not continuous, flow of warm air from the room through the chambers 11 in the opposite direction.

The undesirable circulation of air through the chambers 11 and the deposit therein of moisture 25 and floating particles is minimized, if not entirely prevented, by the provision of closure members 18 for the slots 12 and 13. The members 18 cooperating with the slots 12 extend from the bottom of the slots and terminate a few inches 30 above the bottom of the upper sash 14 when closed. The members 18 cooperating with the slots 13 extend from the pulleys 23 at the top of the slots and terminate a few inches below the top of the lower sash 15 when the sash is in closed 35 position.

The closure members 18 are preferably U-shaped with flanged edges 29 overlapping the exposed surface of the frames adjacent the slots and fastened to the frame in any suitable manner 40 such as by screw bolts 21. The frame members 10 are usually constructed of relatively thin metal and, to impart rigidity thereto adjacent the slots, we provide a pair of members 23 positioned between and respectively contiguous to the slots 12 45 and 13. The members 23 not only provide rigidity for the frame adjacent the points where it is weakened by the slots but are also apertured for connecting the bolts 21 therewith. Rigidity is imparted to the flanged edges 29 by fastening 50 thereto bars or straps 19 through which the bolts 21 extend.

The members 18 each provide a recess 22 extending its full length in which the laterally extending sash members 16 snugly fit and thereby 55 minimize lateral movement of the sashes. The side walls of the members 18 are preferably corrugated, as shown, and the members 16 are of a thickness such that the corrugations yieldingly contact with the sides thereof. The corrugations 60 in the members 18 minimize the frictional resistance of the members 16 therewith and enable the sash to be raised or lowered with slight effort and also effectively prevent any side movement of the sashes by wind action when the sashes are 65 in either open or closed position.

The recesses 22 cooperating with the upper sash are open to the outside atmosphere below the sash and the recesses 22 cooperating with the lower sash open into the room above the sash but, because of the relatively small area of the 5 recesses and the fact that the sash members 16 substantially fill the recesses, there is no perceptible circulation of air through the recesses and the chambers 11 when the sashes are closed.

The closure members 18 also effectively prevent 10 entrance of moisture and of dust laden air into the chamber 11 and as a result rusting of the interior of the frame is minimized if not entirely prevented and there is no necessity for dismantling the frame to remove dust and dirt 15 as is the case with hollow window frames constructed as described but without the combination therewith of closure members embodying the principles of our invention.

Thus it will be seen that we have provided 20 novel improvements in hollow frames for double hung sash windows which substantially seals the interior of the frames against circulation of air therethrough and into or out of the room which prevents the frame chambers from collecting dirt 25 in detrimental amounts and seals the chamber against entrance of atmospheric moisture resulting in rust and premature disintegration.

Having thus described our invention, it is obvious that various immaterial modifications may be 30 made in the same without departing from the spirit of our invention; hence we do not wish to be understood as limiting ourselves to the exact form, construction, arrangement and combination of parts herein shown and described or uses 35 mentioned.

What we claim as new and desire to secure by Letters Patent is:

1. In combination with a hollow metal window frame having its inner side walls both provided 40 with a pair of parallel longitudinally extending guide slots and double hung sashes vertically movable in said frame and each having oppositely projecting guide members reciprocably movable in said slots, U-shaped members forming closures for 45 said slots and extending around said guide members, means fastening the side walls of the closure members to the side walls of the slots, the side walls of each closure member providing vertical corrugations in close fitting engagement with the opposite sides of the guide members enclosed 50 thereby.

2. In combination with a hollow metal window frame having its annular side walls each provided 55 with a longitudinally extending slot adapted to receive a guide member projecting from a sash slidably mounted in the frame, a closure member for each of said slots extending around and spaced from the guide member, said closure members each providing a plurality of corrugations having line contact with opposite sides of the enclosed guide member.
